UNITED STATES PATENT OFFICE.

WALTER S. KING, OF BROOKLYN, NEW YORK, ASSIGNOR TO THE PHENIX TUBE COMPANY, OF SAME PLACE AND JERSEY CITY, NEW JERSEY.

DESIGN FOR A CROWN FOR BICYCLE-FORKS.

SPECIFICATION forming part of Design No. 27,306, dated July 6, 1897.

Application filed May 19, 1897. Serial No. 637,292. Term of patent 7 years.

To all whom it may concern:

Be it known that I, WALTER S. KING, a citizen of the United States, and a resident of Brooklyn, in the county of Kings and State 5 of New York, have invented and produced a new and original Design for Crowns for Bicycle-Forks, of which the following is a specification, reference being had to the accompanying drawings, forming part thereof.

10 Figure 1 is a perspective view of my newly-designed crown for bicycle-forks; and Fig. 2, a section on line 2 2, Fig. 1.

The leading feature of my design consists of a crown for bicycle-forks having a tubular 15 sleeve, a pair of curved tapering wings beneath the same, and a pair of lugs arranged between the wings.

20 *a* represents a tubular sleeve having a flaring lower end *a'* and a straight upright flange *a''*.

b b are a pair of diametrically-placed wings which are curved and tapered from top to bottom.

c c are a pair of diametrically-placed short wings or lugs which are arranged between 25 the wings *b* and are of semicircular form.

The wings *b c* merge at their upper end in an annular flange *d*, arranged at right angles to flange *a''*.

What I claim is—

30 The design for a crown for bicycle-forks, substantially as herein shown and described.

Signed at New York, in the county of New York and State of New York, this 29th day of April, A. D. 1897.

WALTER S. KING.
